(57) **CLAIM**

The ornamental design for an emergency glucose carrying container, as shown and described.

DESCRIPTION

FIG. 1 is a perspective view of the emergency glucose carrying container of the present invention;

FIG. 2 is a top plan view thereof;

FIG. 3 is a front elevational view thereof;

FIG. 4 is a first side elevational view thereof;

FIG. 5 is a rear elevational view thereof;

FIG. 6 is a second side elevational view thereof; and,

FIG. 7 is a bottom plan view thereof.

The broken line showing of environment is included for the purpose of illustrating and forms no part of the claimed design.
